WINDOW CONSTRUCTION

Marshall V. Noecker, Grosse Pointe, Mich., assignor to
Kaufmann Window and Door Corporation, Detroit,
Mich., a corporation of Michigan
Filed Dec. 9, 1964, Ser. No. 417,192
3 Claims. (Cl. 49—450)

This invention relates to a sliding window construction and, more particularly, relates to a combination window construction including improved means for guiding the vertical sliding motion of glass and screened closure panels and for latching the closure panels in partially open or closed positions.

A relatively large number of individual firms are engaged in producing aluminum combination screen and storm windows and the industry is a highly competitive one in which a product improvement, even of a relatively minor nature, may result in a substantial improvement in a firm's competitive position.

A relatively large proportion of the public is familiar with such window constructions on the basis of day-to-day use. Moreover, many of these combination window constructions are bought by home owners who will be using them. Thus, the purchasers of such windows often have a personal interest in certain characteristics of such window constructions and are often attracted by combination constructions which are, for example, low in initial cost, which provide for easy cleaning and operation and which promise to be serviceable over long periods of time without repair. In recognition of the nature of the market, therefore, an abundant and continuing flow of new constructions are evolved by the many manufacturers in the industry. It has thus been as a result of a continuing effort to improve the product that the present invention was developed.

Accordingly, the objects of this invention include:

(1) To provide a combination window construction in which several closure panels, such as storm windows and/or screens, are arranged for sliding in upstanding guideways in a window frame and in which the closure panels may be readily removed from the window frame for cleaning or the like.

(2) To provide a window construction, as aforesaid, in which the window frame is constructed of elongated extrusions and in which the number of discontinuities required in the cross section of such extrusions is minimized to reduce machining costs and to improve the life expectancy of the frame.

(3) To provide a window construction, as aforesaid, in which a notched bar is disposed in at least one of the guideways, the notches of said bar being arranged for alternative engagement by a latching member on the adjacent closure panel for maintaining the storm window or screen in a partially open and closed position.

(4) To provide a window construction, as aforesaid, in which the material of the latching member and notched bar differs from the window frame for providing superior frictional and wear properties and in which the bar is held in place without the use of extra fasteners or the like.

(5) To provide a window construction, as aforesaid, in which a bracket used to fasten the bottom element and adjacent stile of a closure panel also retains the latch member on the closure panel when the closure panel is removed from the window frame.

(6) To provide a window construction, as aforesaid, which is capable of smooth latching and sliding operation, which is sturdily constructed for a long service life and which, moreover, introduces significant economies into the latching and the guiding portions of the device.

Other objects and purposes of this invention will be

2

apparent to persons acquainted with an apparatus of this general type upon reading the following specification and inspecting the accompanying drawings.

In the drawings:

5 FIGURE 1 is an interior elevational view of a window construction embodying the invention.

FIGURE 2 is an enlarged section substantially taken along the line II—II of FIGURE 1.

10 FIGURE 3 is an enlarged sectional view substantially taken on the line III—III of FIGURE 1 with a screened closure panel added thereto.

FIGURE 4 is a partially broken, enlarged and fragmentary oblique view of the upper corner of one of the closure panels of FIGURE 1.

15 FIGURE 5 is an enlarged sectional view substantially as taken on the line V—V of FIGURE 1.

FIGURE 6 is an enlarged fragmentary sectional view substantially as taken on the line VI—VI of FIGURE 2.

20 FIGURE 7 is an enlarged sectional view substantially as taken on the line VII—VII of FIGURE 6.

FIGURE 8 is an enlarged oblique view of the rightward latching member of FIGURE 1.

FIGURE 9 is an enlarged sectional view substantially as taken on the line IX—IX of FIGURE 6.

25 FIGURE 10 is an oblique view of the notched bar shown in cross section in FIGURE 5.

Certain terminology will be used in the following description for convenience in reference only and will not be limiting. The words "upwardly," "downwardly," 30 "rightwardly" and "leftwardly" will designate directions in the drawings to which reference is made. The words "interior" and "exterior" will refer to the normally interior and exterior sides, respectively, of the window construction, those being the right and left sides thereof as 35 appearing in FIGURE 2. The words "inwardly" and "outwardly" will refer to the directions toward and away from, respectively, the geometric center of the construction and designated parts thereof. Said terminology will include the words specifically mentioned, derivatives 40 thereof and words of similar import.

General description

In general, the objects and purposes of the invention are met by providing a window construction which includes a fixed window frame defining a spaced, substantially vertical pair of guideways along which a panel-like closure member, such as a screen or storm window, may slide. An elongated bar is longitudinally aligned with and disposed within at least one of the guideways and has a 45 plurality of notches spaced along the inner edge thereof. A latch member is slideable along the lower edge of the closure member for releasably engaging the notches on the bar to control the latching of the closure member.

Detailed description

55 The combination window construction 10 (FIGURES 1 and 2) embodying the invention includes a frame 11 which includes substantially parallel top and bottom members 12 and 13 connected by a spaced parallel pair 60 of preferably upstanding jambs 16 and 17. In the particular embodiment shown, the window construction 10 comprises a combination storm and screen unit attached by screws 24 to a window casing 20 on a building. The window casing 20 here comprises upper and lower frame pieces 18 and 19 and side frame pieces 21 and 22. In the 65 particular embodiment shown, a spacer sheet 23 is disposed between the bottom member 13 of the frame 11 and the lower piece 19 of the casing 20.

The top and bottom members 12 and 13 and jambs 16 and 17 of the frame 11 are preferably of substantially identical cross section and, in the embodiment shown, are aluminum extrusions. Each member of the frame 11,

for example, the jamb 17 has a wall 26 (FIGURE 3) which comprises spaced exterior and interior portions 27 and 28 perpendicular to the plane of the window frame and integrally connected by an angularly disposed central portion 29. The exterior portion 27 lies inwardly of the interior portion 28 along the plane of the window frame. A mounting flange 31 extends outwardly along the plane of the window construction from the interior edge of the wall 26 for connection to the casing 20. The corresponding mounting flanges 31a and 31b (FIGURE 2) of the top and bottom members 12 and 13 may be used in mounting same as above mentioned with respect to the upper frame piece 18 and spacer sheet 23. Inwardly opening grooves 32, 33 and 34 are provided on the inner faces of the portions 27, 28 and 29, respectively, of the wall 26. The grooves 32, 33 and 34 are preferably identical and extend through more than 180° of a circle. The ends of the grooves 32 and 33, in the present embodiment, receive the threaded ends of sheet metal screws 36 (FIGURE 2) for fastening the top and bottom members 12 and 13 to the jambs 16 and 17.

In the particular embodiment shown, the window construction 10 is of the triple track type capable of supporting three closure members for sliding motion along three separate spaced sets of guideways although it will be apparent that at least the broader aspects of the invention are not limited to such window type.

Parallel guide walls 37, 38, 39 and 41 are integral with and extend inwardly from the wall 26, the inner edges of said guide walls being successively outwardly spaced. The guide wall 37 is located at the exterior edge of the forward portion 27 adjacent the groove 32, the guide wall 38 is located at the joint of the portions 27 and 29 and the walls 39 and 41 are located adjacent the rearward portion of the grooves 34 and 33, respectively. Thus, the walls 37, 38, 39 and 41 define therebetween respective channels or guideways 42, 43 and 44. The inner ends of the guide walls 38, 39 and 41 are flanged toward the interior side of the frame 11 for abutting and guiding the outer edge of adjacent closure members hereinafter described associated with each of the channels 42, 43 and 44. Flanges 51 and 52 extend from the exterior sides of the guide walls 38 and 41 intermediate the ends thereof. Weather seal elements 53 and 54 are disposed in suitable rearwardly facing grooves in the guide walls 37 and 38 adjacent the outer ends thereof for sealing against the exterior surfaces of the exterior pair of members, hereinafter described.

An elongated, substantially rectangular latching bar 61 (FIGURE 10) includes a preferably integral semi-circular bead 62 defining one longitudinal edge thereof which fits snugly within the groove 34 in the jamb 17 (FIGURE 5). The bar 61 extends inwardly from the groove 34 along and in contact with the guide wall 39 to an intermediate point thereon. Pivotal motion of the bar 61 about the axis of the bead 62 is prevented by snug engagement thereof by the mouth of the groove 34. The normally inner edge 63 (FIGURE 10) of the bar 61 is provided with a spaced plurality of triangular, preferably identical notches 64 which terminate adjacent the bead 62. Each notch 64 has a substantially horizontal lower edge 66 and an upper edge 67 which slopes upwardly away therefrom toward the edge 63. The bottom end of the bar 61 defines a downwardly facing and substantially horizontal shoulder 68 beyond which the lower end 69 of the bead 62 extends. The bar 61 is preferably manufactured of a long wearing material having a relatively low coefficient of friction and in the present embodiment is of molded plastic. The bar 61 (FIGURES 5 and 6) is normally installed on the jamb 17, before said jamb is affixed to the bottom member 13, by sliding the bead 62 thereof longitudinally along the groove 34. After the window frame 11 is assembled, the lower bead end 69 rests upon the bottom member 13. The upper end of the bar 61 is preferably located at or slightly below the

bottom edge of the adjacent raised closure member. An identical latching bar, not shown, is preferably similarly disposed on the jamb 16. The groove 34 is preferably upset just above the bar 61 to prevent unintended upward movement thereof.

Closure members 76, 77 and 78 (FIGURES 3 and 5) are slideably and removable disposed in the frame 11 at the channels 42, 43 and 44, respectively. In the particular embodiment shown, the closure members 76 and 77 are storm windows while the closure member 78 is screened. The closure members 76, 77 and 78 may be positioned, for example, to totally glaze the opening of the window frame 11 or alternatively to partially glaze and partially screen said opening to provide ventilation in a substantially conventional manner. In the following description, parts of the closure members 76 and 78 will be referred to by the same reference numerals as corresponding parts of the closure member 77 with the suffixes *a* and *b*, respectively, added thereto. The closure member 77 (FIGURE 1) includes top and bottom elements 81 and 82, connected by upstanding stiles 83 and 84 all of which are preferably of extruded aluminum and have substantially the same cross section, the major exception being that the bottom element 82 carries additional integral portions hereinafter described. The closure members 76 and 78 are provided with corresponding parts. Each of the corresponding parts of the screen 78, for example, the stile 84b (FIGURE 3), carries a rectangular groove 86 on the exterior face thereof in which is disposed an elongated resilient element 87 for holding the edge of a sheet of screening material 88. On the other hand, each of the storm window panels 76 and 77, for example, the panel 77 (FIGURE 5) has an inwardly opening groove 91 along the inner edge of its elements 81 and 82 and stiles 83 and 84, here shown with respect to the stile 84, which is resiliently lined for snug reception of the edge of a sheet of glass 92.

Since in further details of their construction, the closure members 76, 77 and 78 are substantially identical, only one thereof, the closure member 77, need be described. The outer edge of the top member 81 and the stiles 83 and 84 each carry an undercut substantially T-shaped slot 94 (FIGURES 5 and 6) which extends longitudinally theralong. The bottom element 82 (FIGURES 6 and 9) has a preferably identical but downwardly facing slot 96. However, the exterior wall 97 of the bottom elements 82 extends downwardly past the slot 96. A flange 98 integral with the lower end of the wall 97 extends therefrom toward the interior of the building. A fin 99 is integral with and depends from the flange 98 intermediate the edges thereof. The lower portion of the exterior wall 97 and the flange 98 define a substantially rectangular latch groove 102 open on the interior side thereof which communicates at its upper end with the substantially T-shaped slot 96 through the narrow leg portion 103 thereof.

The ends of the elements 81 and 82 and the stiles 83 and 84 are mitered so that the ends of the slots 94 and 96 communicate. The stiles 83 and 84 are joined to the upper element 81 by upper corner brackets 106 and to the bottom element 82 by lower corner brackets 107. The upper corner brackets 106 (FIGURE 4) each comprises a substantially L-shaped member, preferably of a suitable substantially rigid plastic, having legs 108 and 109 fully insertable into the ends of the slots 94 of, for example, the element 81 and stile 84, respectively. The side walls of the slots 94 may then be punched to securely grip the legs of the upper bracket 106. A fin 111 integral with the bracket 106 extends upwardly and outwardly from the corner portion and beyond the edges of the element 81 and stile 84. The portion of the fin 111 above the element 81 is substantially rectangular and the outer end thereof extends beyond the stile 84 to define a pivot portion 112. The rightward end of the fin 111 below the portion 112 extends rightwardly to the narrow portion of the slot 94 and the stile 84. A sub-

stantially rectangular slide plate 114 is supported snugly against the outer edge surface of the stile 84 adjacent the upper end thereof by integral connection through the lower part of the fin 111 to the leg 109.

The closure members 76, 77 and 78 are disposed in their respective channels 42, 43 and 44 in substantially the same way and a description of one thereof will serve for all. FIGURE 3 illustrates the positioning of the pivot portion 112b and slide plate 114b of the screen 78, for example, with the opposed portions of the jamb 17 when said screen 78 is installed in the window construction 10. Here, the exterior face of the stile 84b bears against the interior edge of the flanged inner end of the guide wall 39, the slide plate 114b bears against the inner edge of the guide wall 41 and the pivot portion 112 is disposed between the guide walls 39 and 41 for preventing translation of the screen 78 out of the interior side of the frame 11 when the screen is in its sliding position. It will be noted that the pivot portion 112b does not interfere with the flange 52. Similarly, FIGURE 2 illustrates the positioning of the upstanding fin 111a on the storm window 76, here for example, the fin 111a extends upwardly past the lower end of the guide wall 38 of the top member 12 to provide additional resistance to movement of said window 76 out of the interior side of the frame 11 when said window is in its upwardmost position.

The lower corner brackets 107 (FIGURE 6) are substantially similar to the upper corner brackets 106 above described except that the portion of the fin 111 which extends vertically of the leg 108 and includes the pivot portion 112 has no corresponding part in the brackets 107. Thus, the rightward corner bracket 107 (FIGURE 6), for example, has horizontal and vertical legs 118 and 119 disposed in the slots 96 and 94, respectively, of the bottom element 82 and stile 84, respectively, and a slide plate 124 vertically aligned with the above-mentioned slide plate 114 adjacent the outer edge of the stile 84 and connected to the vertical leg 119 by a narrow lock 123. Since the latching bar 61 does not participate in guiding the closure member 77 along the jambs 16 and 17, substantially no loads are placed thereon transverse to the plane of the window construction 10 as are imposed on the guide walls 37, 38, 39 and 41.

Each of the closure members 76, 77 and 78 includes a pair of latching members and since said closure members are preferably identical in this regard, only the latching members of the closure member 77 need be described in detail. The closure member 77 thus has a pair of elongated latching members 126 and 127 (FIGURE 1) at opposite ends of the groove 102. Since the latching members 126 and 127 are preferably mirror images of each other, a description of the latching member 127 will suffice for both. The latching member 127 (FIGURES 6, 7, 8 and 9) comprises substantially rectangular inner and outer body parts 128 and 129 which are slideably but snugly disposed within the groove 102. The body parts 128 and 129 are longitudinally spaced to define a finger opening 131 into which the finger of the user may be inserted to slide the latching member 127 inwardly along the groove 102. The finger opening 131, in extending through the full thickness of the latching member 127, provides the maximum possible depth and, hence, minimizes any tendency for the user's fingers to slip out therefrom. The body parts 128 and 129 may, if desired, be recessed along the exterior side thereof as indicated at 132 and 133 (FIGURE 8). An upstanding ridge 134 of substantially T-shaped cross section (FIGURES 6 and 9) connects and is preferably integral with the upper surfaces of the body parts 128 and 129. The ridge 134 is snugly and slideably disposed within the slot 96. The maximum thickness of the ridge 134 is greater than the width of the outer portion 103 of the slot 96. Since the ridge 134 cannot therefore move downwardly out of the slot 96, the latching member 127 cannot move transversely out of the groove 102. The latch member 127 is installed on the

closure members 77 by sliding same into the rightward ends of the groove 102 and slot 96 prior to installation of the corner bracket 107. An upstanding guide fin 136 is preferably integral with the upper surface of the outer body part 129 at a point outwardly spaced from the end of the ridge 134 and snugly but slideably extends upwardly into the narrow portion 103 of the slot 96 to maintain the outer end of the body part 129 in alignment with the groove 102.

10 A helical compression spring 138 lies in the slot 96 (FIGURES 6 and 7) between a tape 139 upset into the slot 96 from the interior wall thereof and a knot 137 on the inner end of the ridge 134 for urging the latch member 127 outwardly along the groove 102. Interference between the ridge 134 and the adjacent inner end of the horizontal leg 118 of the corner bracket 107 limits the maximum outward movement of the latch member 127.

15 The rightward end of the body part 129 terminates in a stepped nose 141 (FIGURES 5, 6 and 8). The nose 141 is of lesser thickness than the body part 129, the interior surfaces thereof being displaced to define an outwardly facing, substantially vertical shoulder 143 at the boundary therebetween. The bottom edge 144 of the nose 141 is a horizontal extension of that of the body part 129. The upper edge of the nose 141 is downwardly stepped through a riser surface 148 at a point outwardly spaced from the shoulder 143 to define an upwardly facing and preferably horizontal lock surface 146. The outer edge 147 of the nose 141 slopes upwardly and inwardly from the bottom edge 144 preferably at the same slope as the upper edge 67 of the notches 64 on the bar 61, here approximately 60°. The riser 148 may be similarly sloped if desired. The outer edge 147 is shorter than the upper edge 67 of the notches 64. The latching member 127 preferably 20 comprises a monolithic piece of a substantially rigid plastic or other suitable long wearing material having a relatively low co-efficient of friction.

25 Should the latching member 126 be provided with a latching bar corresponding to the latching bar 61, it will be understood that the member 126 will be activated and will react in substantially the same manner as the member 127 and, hence, discussion of the operation of the member 127 will suffice for both. Thus, when the closure member 77 is at its lowest point in the frame 11 (FIGURES 40 1, 2 and 6), the lock surface 146 (FIGURE 6) of the latching member 127 lies below the shoulder 68 on the bar 61 which prevents upward movement of the closure member 77. The closure member 77 is thus locked in position and cannot be opened from the exterior side 45 thereof. The closure member 77 may be raised after moving the latch member 127 inwardly sufficiently that the lock surface 146 no longer interferes with the bar step 68. Whereafter further inward movement of the latching member 127 may be accomplished either by continued direct manual actuation thereof or by cammed actuation of the outer nose edge 147 as it slides upwardly along the inner end of the shoulder 68. After the latching member 127 has been freed at the shoulder 68, direct manual actuation of the latching member 127 is no longer required during raising of the closure member 77. As the rising latch member 127 reaches a notch 64, the spring 138 will impel the nose 141 of said member into said notch as indicated in broken lines at 141c in FIGURE 6. 50 If desired, the closure member 77 may be left at such position with the lower edge 66 of the notch 64 supporting the bottom edge of the nose 141 to prevent downward movement of the closure member 77 due to gravity. On the other hand, upward movement of the closure member 77 may be continued past one or more of the notches 64 without attention to the latching member 127, the upwardly moving nose edge 147 sliding against the upper edge 67 of each succeeding notch to cam the latching member 127 inwardly. As the closure member 77 approaches its uppermost position, as determined by inter-

ference thereof with the top frame member 12, the latching member 127 vertically passes the upper end of the bar 61 and hence is no longer outwardly limited thereby. Thus, the spring 38 moves the latching member 127 outwardly sufficiently that the bottom edge of the nose 141 rests on top of the upper end of the bar 61, as indicated in broken lines at 141d in FIGURE 6, thus preventing unintended downward movement of the closure member 77.

In the present embodiment, the flange 52 (FIGURE 2) on the jamb 17 is slotted near the lower end thereof and intermediate the ends thereof as indicated at 151 and 152, respectively, for reception of a latching member, not shown, on the screen 78, corresponding to the above-mentioned member 127 to allow the screen 78 to be locked either in its uppermost or lowermost position. Although additional slots can be provided for providing intermediate positions of the screen such usually is not necessary and moreover such slots are relatively difficult and expensive to produce due to the relatively inaccessible position of the flange 52 within the channel 44. It will be apparent that a plurality of slots would be disadvantageous to provide as compared to the notched bar 61 for the closure member 77. The closure member 76 may be locked in its normal uppermost position shown in FIGURE 2 by means of the latching member 127a thereof and a suitable slot, not shown, in the flange 51 comparable to the slot 152.

In the present embodiment of the invention, interlocking flanges are provided on the normally adjacent edges of adjacent closure members normally disposed at opposite vertical ends of the frame 11 to improve the weather seal between such edges by preventing separation thereof transverse to the plane of the frame 11. Thus, the interior face of the bottom element 82a of the normally upper member 76 is provided with an upturned, substantially L-shaped flange 153 (FIGURE 9) which is engageable by a corresponding downward turned flange 154 (FIGURE 2) on the exterior face of the top element 81 of the closure member 77.

It is contemplated that, if desired, a bar corresponding to the bar 61 might be placed in the groove 33 upon the deletion of the flange 52, the latching members of the screen 78 thus interacting with said bar in a manner described with respect to the latching member 127 and bar 61 to allow the screen 78 to be adjusted to several stable positions intermediate the ends of its travel.

Operation

Although the operation of the window construction embodying the invention has been substantially indicated hereinabove, the broader aspects thereof will be reviewed to insure a complete understanding of its operation. When the window construction 10 is used as a storm window, the exterior closure member 76 is normally disposed in its uppermost position as in FIGURE 2 and the intermediate closure member 77 is locked in its lowermost position to provide complete closure of the window opening in a substantially conventional manner. Similarly, the screen 78 may be positioned at either end of its travel and the opposed one of the members 76 and 77 may be opened to the extent desired as to provide ventilation in a substantially conventional manner. Moreover, the closure members when at the limits of their travel cannot be opened from the exterior side of the window construction.

Each of the closure members, for example, the member 77 is held against interior movement by interference of the pivot portion 112 of each of the upper corner brackets 106 thereof and of the nose 141 of each of the latching members 126 and 127 thereof with the guide wall 39 of the jambs 16 and 17. When in its uppermost position, each of the members 76, 77 and 78, for example, the member 76, is further prevented from interior movement by interference of the upper ends of the fins 111a or the upper corner brackets 106a thereof with the adja-

cent guide wall of the top member 12. When in its lowermost position, each of the members 76, 77 and 78, for example, the closure member 77, is prevented from interior movement by interference between the depending fin 99 thereof with the adjacent guide wall of the bottom frame member 13.

The closure member 77, as well as the other members 76 and 78, may be opened from its closed position of FIGURE 2 upon release of the latching member 127 (and the member 126 if provided with a latching bar corresponding to the bar 61) and may be thereafter stopped at any of the relatively large number of intermediate positions or in its uppermost position as determined by interaction of the latching member 127 with the notched bar 61 as hereinabove described.

The closure members 78, 77 and 76, in that sequence, may be readily removed from the frame 11 all in the same manner. The closure member 77 may be removed from the frame 11 by moving the latching members 126 and 127 inwardly sufficiently that they clear the corresponding rearwardly adjacent guide walls of the jambs 16 and 17. Thereafter, the bottom element 82 of the closure member 77 may be pivoted through and past the interior side of the frame 11 about the common axis of the pivot portions 112. Finally, the closure member 77 may be pivoted to move one of the pivot portions 112 upwardly and the other pivot portion 112 downwardly to release same from the jambs 16 and 17.

The closure member 77 may be replaced in the frame 11 by reversing the above steps.

Although a particular preferred embodiment of the invention has been disclosed above for illustrative purposes, it will be understood that variations or modifications thereof which lie within the scope of the appended claims are fully contemplated.

The embodiments of the invention in which an exclusive property or privilege is claimed are defined as follows:

1. In a window construction in which a closure member is disposed for substantially vertical sliding movement; a pair of fixed upstanding jambs along which said closure member may be moved; a semicircular groove closed through an arc of more than 180°, said groove opening inwardly of said window construction and extending longitudinally along at least one of said jambs; an elongated bar of rigid plastic having a semicircular bead along one longitudinal edge which is snugly disposed in one of said grooves for maintaining said bar upright and fixed with respect to said jamb, said bar having a plurality of substantially V-shaped notches spaced along the other longitudinal edge thereof, said notches having a substantially horizontal lower edge and a divergently sloped upper edge, the lower end of said bar forming a downwardly facing shoulder which is substantially the depth of said notches and downwardly past which said bead extends; means on said closure member engageable with said bar to regulate movement thereof, said means comprising at least one rigid plastic latch member supported on said closure member, said latch member having a nose resiliently urged for extending from said closure member toward said bar and releasably engageable with said jamb to prevent interiorwise movement of said closure member, said nose being reduced in thickness transversely of the plane of said closure member, the outer end of said nose having an upwardly facing lock surface stepped vertically below the upper face of the rest of said latch member and adapted for engagement with and beneath said shoulder on said bar to lock the closure panel in a closed position said lock surface being capable of partially entering said notches, the outer end of said nose terminating in the downwardly and outwardly sloped ramp shaped similarly to said notches but of lesser depth and adapted for entry fully therewith whereby said ramp allows said notches to cam said latch member out of engagement therewith on raising said closure member, the reduced

height of said lock surface allows locking of said latch member against said shoulder and the unreduced height of the inner portion of said nose provides greater area of contact with said jamb for resisting interiorly directed forces on the closure member.

5

2. In a window construction including a closure member, the combination comprising: a bottom rail in said closure member, the interior face of which bottom rail bears a rectangular latch groove which communicates at its upper end with a downwardly opening slot, said rail having opposed flanges at the interface between said slot and said groove to restrict the size of the opening therebetween; a stile upstanding from said bottom rail and having an outwardly opening slot; a substantially L-shaped corner brace having a leg disposed in and fixed with respect to each of said slots at the adjacent ends thereof; a rigid nonmetallic latch member disposed in and slideable along said latch groove, said latch member having a T-shaped ridge extending upwardly into said downwardly opening slot so as to be snugly and slidably disposed therewithin, the opposed flanges of said rail member extending beneath the head of the T-shaped ridge for locking the latch member within the rail; a compression spring in said slot having one end thereof fixed with respect to said closure member and the other end thereof bearing on said ridge, said ridge being located between said spring and said corner brace; whereby said spring urges said latch member outwardly along said groove and said corner brace limits the extent to which said latch member moves in response to such urging, said latch member including first and second rectangular portions respectively having planar upper and lower external surfaces slidably received in and each bearing against the opposed surface of the latch groove, said first and second portions being laterally spaced from each other to define a hand opening therebetween, said first and second portions being contained within the cross section of said groove and extending the full depth of said groove to maximize the depth of said hand opening, opposite ends of said T-shaped ridge being integrally connected with the upper surfaces of said first and second portions for rigidly connecting same, the end of said first portion remotely located from said second portion extendable longitudinally from said groove and defining a nose engageable with a fixed, opposed rack for locking said closure member said first portion being further formed with a guide rib centered on the upper surface thereof adjacent said nose and in spaced relation to said T-shaped ridge and extending between opposed flanges of the rail member for guiding the nose end of the latch member along said groove.

3. In a window construction including a closure member disposed for substantially vertical sliding movement, the combination comprising:

15

a lower frame element and fixed jamb upstanding therefrom and along which said closure member may be moved, said jamb including interior and exterior walls, an interiorly extending flange at the inner end said interior wall opposed to said closure member, ridges extending from said interior wall defining a semicircular groove tangent to said interior wall and opening toward said closure member;

20

a flat, elongated bar of rectangular cross section disposed between said interior and exterior walls, the width of the interior side face of said bar snugly abutting said interior wall to positively locate said bar against interiorwise movement, said bar having

opposed longitudinal grooves in the flat side faces thereof and a rounded outer edge which define a semicircular bead snugly but slidably receivable in said semicircular groove in said jamb, said ridges entering snugly into said opposed grooves to prevent said bar from pivoting on the axis of said bead in an exterior direction, a plurality of V-shaped notches spaced along the inner edge of said bar and opposing said closure member, said notches having horizontal lower reaches and upwardly and inwardly sloped, linear upper reaches extending from said lower reaches, the apex of said notches being located at said opposed grooves in said side walls, the bottom portion of said bar below said notches being omitted to define a downwardly facing shoulder, said bar being vertically supported by the lower end of said semicircular bead on said lower frame element; a U-shaped, interiorly opening latch groove extending along the bottom of said closure member, said latch groove opening through the side edge of said closure member in opposition to said interiorly extending flange and said notched bar, and means defining a slot directly above said latch groove; latch member having rectangular inner and outer portions spaced along said latch groove for receiving fingers of an operator therebetween, said outer portion of said latch member including a nose portion for coaction with said notched bar, the interior face of said nose portion paralleling the interior face of said inner and outer portions but being stepped exteriorly therefrom and defining a shoulder surface opposed to said flange, whereby the reduced width of said nose portion is receivable between said exterior and interior jamb walls and is positively guided by snug sliding engagement with said interior wall into engagement with said notched bar, the upper surface of said nose portion being downwardly stepped at a point spaced from the outer end thereof for defining an upwardly facing horizontal lock surface, said nose terminating in a downwardly and outwardly sloped linear ramp extending from said lock surface to the lower wall of said outer portion, the slopes of said ramp surface and said notches being similar to allow said upper notch reaches to cam said nose inwardly when said closure member is raised, said ramp being shorter than said notches in said bar so that said lock surface is extendable partially into said notches, said locking surface being snugly and slidably insertable beneath said shoulder on said bar when said closure member is at its lowermost position with respect to said jamb to lock said closure member in a closed position.
